UNITED STATES PATENT OFFICE

171,029

TOOTHBRUSH CABINET

Garlin J. Coleman, New York, N. Y.

Application March 8, 1952, Serial No. 18,832

Term of patent 7 years

(Cl. D4—3)

To all whom it may concern:

Be it known that I, Garlin J. Coleman, a citizen of the United States, residing at New York, in the county of New York and State of New York, have invented a new, original, and ornamental Design for a Toothbrush Cabinet, of which the following is a specification, reference being had to the accompanying drawing, forming part thereof.

In the drawing:

Fig. 1 is a front perspective view of a toothbrush cabinet, showing my new design;

Fig. 2 is another perspective view of the cabinet, showing the cabinet with its door in the open position; and

Fig. 3 is a rear perspective view of Fig. 1.

I claim:

The ornamental design for a toothbrush cabinet, as shown.

GARLIN J. COLEMAN.
